UNITED STATES PATENT OFFICE.

HJALMAR W. RANNIKKO, OF WILMINGTON, CALIFORNIA.

CONCRETE ROD PULLER.

Application filed November 1, 1926. Serial No. 145,584.

My invention is a concrete rod puller for pulling rods from concrete after the concrete has been sufficiently set to allow removal of the forms.

5 An object of my invention is a pulling machine or a jack which may be utilized to pull rods from concrete structures, such rods being usually used in holding the forms, as in the construction of walls or the like, and 10 the rods are pulled either before or after the forms are removed.

Another object of my invention is to pull the rods with a straight pull so that they will not become bent in the pulling operation 15 and also to engage the rods with pressure dogs or wedges on opposite sides so that the rods will be evenly stressed in the pulling.

A further object of my invention is to pull the rods in a succession of short movements of the gripping dogs and in the return movements to positively hold the rods to prevent same from being pressed back into the concrete. With the use of my rod puller the rod so withdrawn from the concrete 20 structure may be utilized again without any straightening or manipulation of any kind.

My invention, as illustrated in the accompanying drawings, in which:

25 Figure 1 is a side elevation of my rod puller, as if taken in the direction of arrow 1 of Fig. 2.

Figure 2 is a plan view taken in the direction of arrow 2 of Fig. 1.

30 Figure 3 is a transverse section on the line 3—3 of Fig. 2.

Figure 4 is a perspective view of the gripping wedges.

35 Figure 5 is a detail of the arrangement for holding the gripping wedges suspended.

In the drawings a concrete structure may indicate a vertical wall or the like. The pulling device has a base 1 and at its forward end a pair of posts 2, spaced apart, 40 extending outwardly at right angles to the base, these being rigidly secured to the base and also having lugs 3 rigidly connected to the base and to the posts. A column 4 extends upwardly from the base parallel to the 45 posts and is spaced midway between same. This column has a pair of ears 5 at its upper end.

50 A lifting lever 6 is mounted on a heavy pivot pin 7 through the ears 5 and extends between the posts 3 having divided outer ends 8 and 9.

A lifting block 10 has a pair of passages 11 therethrough and is fitted to slide on the posts 2. A neck 12 fits between the ends 8 and 9 of the lifting lever 6, there being 60 a head 13 engaging underneath such ends. The block has an opening 14 from side to side closed by cover plates 15, wedges 16 slidably mounted in the block, and the block and the wedges have co-acting surfaces 17. 65 Each of the wedges has a series of somewhat semi-circular gripping teeth 18 in order to grip the sides of the rods 19, slideable through an aperture 19' in the base, to pull same outwardly, a lifting rod 20 is secured to each of 70 the wedges fitting in a socket 21 and being secured by a pin therein, the rods pass through an opening 22 in the upper part of the block. Coiled springs 23 are under compression tending to force the wedges downwardly, and coiled springs 24 on the upper part of the lifting rods engage angular levers 25 pivotally connected to the upper ends of the lifting rods by pins 26. By this construction, when the levers are shifted 75 from the position shown in Fig. 5 so that the free end is lowermost, the upper springs are compressed and lift the wedges upwardly, compressing the lower springs. This action is sufficient to free the wedges from 80 engagement with any of the usual sized rods being pulled.

85 A dog 27 is pivotally mounted in a bracket 28 having gripping teeth 29 and is actuated by a spring 30 normally forcing the teeth 90 into engagement with the rod being pulled.

The power lever 31 has a socket 32 for a handle 33, or other leverage arm, and is provided at its lower end with a yoke 34, the arms of the yoke being connected by a heavy 95 pivot pin 35 to the lugs 3. A heavy pressure pin 36 extends transversely between the arms of the yoke and has a pair of rollers 37 mounted thereon. These rollers, in the upward movement of the power lever, engage 100 the under surface 38 of the lifting lever and force same upwardly. In order to draw the lifting lever downwardly an arm 39 is attached to a hub 40, this hub being free to rotate on the pin 36, the arm having a roller 105 41 engaging the upper surface 42 of the lifting levers, therefore in the downward movement of the power lever 31, the lifting levers are pulled downwardly.

110 The manner of using and functioning of my concrete rod puller is substantially as follows: The device is fitted over a project-

ing rod from a concrete structure, preferably after the forms have been removed, the rod fitting through the aperture 19' and extending through the head 13, the neck 12, and the main portion of the block 10. The wedges 16 are pressed by the springs 23 into close engagement with the rod after the angle lever 25 has been shifted to the position shown in Fig. 5, then presuming the device is in the position of Figs. 1 and 2 and the power lever 31 is moved upwardly, that is swinging in a counter-clockwise direction, the rollers 37, on the pin 36 running on the under surface 38 of the lifting lever 6, elevate such lever. This lever, by means of the separated ends 8 and 9, lifts upwardly on the block 10 and in this action the wedges are forced into tight engagement with the rod and elevate same until the power lever occupies a position substantially parallel to the posts 2. On the downward movement of the power lever 31, the dog 27 being spring pressed, grips the rod and prevents it being forced backwardly into the concrete. The downward movement of the power lever 31 towards the wall causes the arm 39 to pull on the lifting lever 6, due to its engagement with the surface 42. This engagement need be only on one of the ends 8 or 9, and as shown on the end 9. By continuous up and down movements of the lower lever, that is from and towards the wall, the rod is given an outward pull from the concrete in intermittent motions until either completely removed or sufficiently loosened to be moved by hand.

It will be seen by my device that I secure very great leverage having the power lever act on the lifting lever and while the length of the stroke is not particularly great compared with the movement of the power lever, nevertheless the force exerted on the rod to pull same is many fold the amount of power required to be applied to the power lever, especially when using a handle 33 of some length. It is to be noted that the pull on the rod is straight and that the rod is always pulled with a tension parallel to the posts and moreover that there is no squeezing action on one side only which would tend to give the rod a slight bend or a curve after leaving the pulling device. Therefore in my construction of a concrete rod puller, the rods are pulled straight without distortion and may be used over again. If the rods are pulled before the concrete grips same too tightly or if they are not imbedded in too great a thickness of concrete, the adherence between the rods and the concrete will be broken before the elastic limit of the rods usually used in concrete construction is reached.

With my construction of rod puller, the device is held securely in place against the concrete wall or the forms and does not re-

quire manual manipulation to hold it in place as the dog 27 grips the rod being pulled between the pulling strokes and hence prevents the device from loosening. Therefore, the dog functions both to hold the device in place while the rod is tight in the concrete and, as the rod becomes loosened, prevents same from being thrust back and into the wall.

Various changes may be made in the principles of my invention without departing from the spirit thereof, as set forth in the description, drawings and claims.

I claim:

1. A rod puller comprising in combination, a base having a pair of guide posts, a block having rod gripping devices slidably mounted on said posts, a lifting lever, means forming a pivotal connection of same with the base, a power lever, means forming a pivotal connection of same with the base, and means to interengage the power lever and lifting lever, the lifting lever acting on the block.

2. A rod puller, as claimed in claim 1, having means inter-connecting the power lever and the lifting lever to return said lifting lever to its initial position on the return movement of the power lever.

3. A rod puller comprising in combination, a base, a plurality of guide posts fixedly secured thereto, a block slidably mounted on said posts, gripping wedges slidably in said block to grip a rod, a lifting lever engaging said block, means forming a pivotal connection between said lever and the base, a power lever pivotally connected to the base, a pressure pin on the power lever, said pin engaging a surface of the lifting lever to actuate same on movement in one direction of the power lever.

4. A rod puller, as claimed in claim 3, an arm pivotally connected to the power lever and slidably engaging the lifting lever to return said lever to its initial position on movement of the power lever.

5. A rod puller comprising in combination, a base, a plurality of guide posts rigidly connected thereto, a column fixedly secured to the base, a lifting lever pivotally connected to the column and extending between the said posts, a block slidably mounted on the posts engaging the upper and lower surface of the lifting lever, gripping wedges slidably mounted in the block, a power lever pivotally connected to the base, a pressure pin on said power lever, said pin engaging the lifting lever in one direction of movement on an under surface.

6. A rod puller, as claimed in claim 5, an arm pivotally connected to the pressure pin and having a sliding engagement with the upper surface of the lifting lever to return same to its initial position on the return movement of the power lever.

7. A rod puller, as claimed in claim 5, the block having an opening therethrough the said gripping wedges operating in said opening, lifting rods connected to said gripping wedges, and means to raise and lower said rods to bring the wedges out of engagement from a rod.

8. In a rod puller, a base having a plurality of guide posts, a block slidably mounted on said posts having an opening therein, gripping wedges slidably mounted in said opening, lifting rods connected to the gripping wedges, means to raise and lower said lifting rods to disengage and engage a rod being pulled, and means to shift the block to pull a rod.

9. In a rod puller, a base, a plurality of guide posts rigidly connected thereto, a block slidably mounted on said posts and having a plurality of gripping wedges slideable therein, means to shift said wedges to engage or disengage a rod being pulled, a dog pivotally connected to the base to engage a rod and prevent its being forced in reverse direction, and means operable on the block to slide same in a direction to pull a rod and in a direction to secure a second grip on the rod being pulled.

In testimony whereof I have signed my name to this specification.

HJALMAR W. RANNIKKO.
